Inventor:

Miss L. P. Stearn
Attorney.

UNITED STATES PATENT OFFICE.

PEARL Y. SMILEY, OF KITCHENER, QUEBEC, CANADA.

BOOT.

Application filed September 9, 1921. Serial No. 499,426.

To all whom it may concern:

Be it known that I, PEARL Y. SMILEY, of the city of Kitchener, Province of Quebec, Dominion of Canada, a subject of the King 5 of Great Britain, have invented certain new and useful Improvements in Boots; and I do hereby declare that the following is a full, clear, and exact description thereof.

My invention relates particularly to boots 10 for use by lumbermen, firemen and other persons whose occupation exposes them to rain and fallen snow and has for its object to provide a boot which possesses warmth and waterproof qualities and which is 15 adapted to fit snugly the leg of the wearer between the calf and the knee and have the trousers of the wearer overlap its top.

To this end the invention may be said to consist of a rubber knee boot, the foot and 20 ankle portions of which are of the usual comparatively stiff construction and the upper portion to the knee of rubberized stockingette and provided with a garter to cause this pliable portion to clasp the leg just below the knee.

For full comprehension, however, of my invention reference must be had to the accompanying drawings in which similar reference characters indicate the same parts 30 and wherein:

Figure 1 is a side elevation of a boot manufactured according to my invention;

Figure 2 is a similar view of the opposite side of the boot;

Figure 3 is a view similar to Figure 1 partly in section; and

Figure 4 illustrates a boot as worn.

The foot and ankle portions of my improved boot are indicated at *b* and *c* and 40 the top stockingette portion at *d*. This latter portion is adapted to be drawn together to clasp the wearer's leg between the calf and the knee by a garter *e* secured at one end by a fastener *f* to the stockingette portion near the top edge thereof while its opposite end is adapted to engage a buckle *g* fastened to the stockingette portion in line with the strap.

The stockingette portion consists of wool 50 or other warm lining of suitable material extending from the sole to the top. The lower leg portion, ankle and foot are reinforced and stiffened in the usual manner while the top or stockingette portion is made

flexible and waterproof by a heavy coating 55 of rubber without stiffening.

As shown in Figure 5 the boot owing to the pliability of its top readily conforms to the leg of the wearer with a snug fit when the garter is tightened.

This construction and arrangement of parts provides a rubber boot the pliable top of which will not slip down when the wearer is moving about nor will the garter interfere with blood circulation or the wearer's 60 comfort as the garter may be left relatively loose and yet be incapable of downward displacement over the calf of the leg.

What I claim is as follows:

1. A rubber or rubberoid knee boot having comparatively stiff pliable foot and ankle portions the latter extending to a point substantially half way between the ankle and the knee and a pliable top portion and means whereby said pliable portion is 75 caused to snugly fit the leg of the wearer between the calf and the knee, all of said portions being waterproof.

2. A rubber or rubberoid knee boot having comparatively stiff foot and ankle portions the latter extending to a point substantially half way between the ankle and the knee and a pliable top portion and a garter for causing the latter portion to clasp 80 the leg of the wearer between the calf and the knee, all of said portions being waterproof.

3. A rubber or rubberoid knee boot having comparatively stiff foot and ankle portions the latter extending to a point substantially half way between the ankle and the knee and a pliable stockingette top portion extending to the knee and adapted to be drawn in to clasp the leg of the wearer between the calf and the knee and means 90 whereby the stockingette portion is caused to clasp the wearer's leg, said means consisting of a strap secured to the stockingette portion and a buckle also secured to said portion and adapted to be engaged by the 95 strap, all of said portions being waterproof.

In testimony whereof I have signed my name to this specification in the presence of two witnesses.

PEARL Y. SMILEY.
